(57) **CLAIM**

The ornamental design for a vehicle rear light unit, as shown and described.

DESCRIPTION

FIG. 1 is perspective view from the front left of a vehicle rear light unit. The drawings and descriptions represent the left side embodiment. The design also contemplates a mirror symmetrical embodiment on the right side of the vehicle. The dash line included denotes environment and is not part of the claimed design

FIG. 2 is a front elevation view thereof;

FIG. 3 is a left elevation view thereof, and,

FIG. 4 is a top view thereof.
